Attorney

UNITED STATES PATENT OFFICE

WINFIELD C. PATT, OF AUBURN, RHODE ISLAND, ASSIGNOR TO L. G. BALFOUR COMPANY, OF ATTLEBORO, MASSACHUSETTS, A CORPORATION OF MASSACHUSETTS

FINGER RING

Application filed September 24, 1929. Serial No. 394,780.

My invention relates to emblem finger rings of the type wherein the ornamental insignia of the mounting is exposed above a stone.

Heretofore in this type of ring the metal insignia or ornament rested clamped upon the exposed face of the stone by pegs or screw passing through holes in the stone. This involved drilling which cracked, weakened, and sometimes destroyed the stone or ornament, and involved a great labor expense.

The essential objects of my invention are to avoid drilling or otherwise mutilating, weakening, or destroying the stone; to accommodate the setting for stones of various thicknesses; to enable the use of stones of different circumferential dimensions without unsightliness or ingress of dirt; to enable the mounting of the stone without a lateral incision of the ring head; and to attain these ends in a structure inexpensive and easy to construct.

To the above ends essentially my invention consists in such parts and in such combinations of parts as fall within the scope of the appended claims.

In the accompanying drawings which form a part of this specification,

Figures 1 and 2 are a top plan view and a side elevation respectively of a ring embodying my invention,

Figure 3, an enlarged fragmentary section of the same on line 3—3 of Figure 1,

Figure 4, a perspective view of the stone and its contiguous parts assembled preparatory to mounting, and

Figures 5, 6 and 7, similar views respectively of the ring, stone, and cup disassembled.

Like reference characters indicate like parts throughout the views.

As herein shown the ring comprises the shank 10 and head or table 11. The latter is centrally bored to form a vertically disposed hole or opening 13, in this instance peripherally elliptical in outline.

Integral with or fixed to the upper face of the table is an ornamental housing plate 15 provided with a central elliptical recess 16 substantially coinciding with the opening 13.

The plate comprises an elliptical frame 18 bounding the recess 16, and a central ornament, emblem, or insignia 17 covering the recess provided with visual apertures or interstices 19 opening into the recess. These apertures are optionally and artistically arranged in number and shape to conform to the particular figure constituting the ornament. In this instance the apertures are four in number.

The opening 13 and recess 16 form a seat for the stone and its contiguous parts. In detail the stone 20 may be of any desired quality, precious or nonprecious, and of any preferred color. Its peripheral outline corresponds in shape to that of the seat, which in this instance is elliptical. These stones commercially vary more or less in thickness and lateral dimensions. The stone before insertion into the ring is more or less encased in metal thus. The stone is placed in a supporting member 22 comprising an elliptical plate 23 and preferably a vertical flange 24. An open cap 26, as shown in Figure 5, comprises an elliptical ring or band 27 provided with an inwardly directed peripheral bead or flange 28. This flange overlaps the upper marginal face of the stone and supports the ring 27 which surrounds the stone. The combined height of the flange 24 and of the ring 27 is slightly less than the height of the stone, so as to accommodate the members 22 and 26 to stones of differing thicknesses. The flange 28 of the ring 27 serves the additional purpose of concealing from above any peripheral space which may occur between the ring and stone when the latter varies in diameter, and also prevents the ingress of dust and dirt.

The stone, substantially enclosed with the exception of its open top, is manually slid into its seat with the flange 28 or the stone 20 in contact with the portion 17 of the plate, and is fixed therein by the insertion of solder between the periphery of the plate 23 and the ring head or table 11, as at 30.

It will be observed that the insignia 17, carried by or integral with the plate 15 has, by virtue of the interstices or apertures 19 which expose the stone 20, the appearance of an or-

nement fixed directly to the stone. Further, that no rivets, screws, or other elements injurious to the stone are employed, nor does the insertion of the stone into the ring head 5 involve any lateral incision in the latter. The members 22 and 26 upon the exterior of the stone facilitates the assembling of the ring.

The form of ring shown combines all the 10 advantages hereinabove set forth, but it will be understood that rings may be designed which will embody some of the advantages without embodying all, and that such rings would be within the invention, the various 15 features of which are not limited in their scope to construction in which all said features are present.

I claim:—

1. A finger ring or the like having a table, 20 a vertical bore extending therethrough, an insignia plate spanning the upper end of said bore but leaving exposed visual openings, a stone within said bore, means for supporting said stone with its top surface adjacent said insignia plate and an open top metal cap, the interior of which fits said stone and the exterior of which fits said bore.

2. A finger ring or the like having a table, 30 a housing plate mounted thereon, a vertical bore extending through the housing plate and table, an insignia plate mounted on said housing plate and spanning the upper end of the bore but leaving exposed visual openings, a stone within said bore, means for supporting 35 said stone with its top surface adjacent said insignia plate and an open top metal cap, the interior of which fits the stone and the exterior of which fits said bore.

3. A finger ring or the like having a table, 40 a vertical bore extending therethrough, an insignia plate spanning the upper end of the bore but leaving exposed visual openings, a stone within said bore, a cup for supporting the stone with its top adjacent said insignia 45 plate, and an open top metal cap, the interior of which fits said stone and the exterior of which fits said bore.

4. A finger ring or the like having a table, 50 a vertical bore extending therethrough, an insignia plate spanning the upper end of the bore but leaving exposed visual openings, a stone within said bore, means for supporting said stone with its top surface adjacent said insignia plate and an open top metal cap, 55 the interior of which fits said stone and the exterior of which fits said bore, said cap forming a rim at the upper end of said bore.

In testimony whereof I have affixed my signature.

60 WINFIELD C. PATT.
